Granville Martin
Letters Patent

The Schedule referred to in these Letters Patent
and making part of the same containing a descrip-
tion in the words of the said Granville Martin
himself of his improvement in the method of
making four tined or pronged forks for pitch-
ing, digging gardens and other uses.

Be it known that I the said
Granville Martin have invented and applied to
use a new and useful improvement in the man-
ner, and method of constructing and making
four tined or pronged forks for pitch-
ing, digging gardens and other uses. This invention or in-
-provement consists principally in the mode of draw-
ing the two middle tines, which I specify thus

I take a bar of steel four or five inches long
and having a shank on one end split the other
into four strips turn off the two outside strips at
right angles with the shank and draw the other
two together in the same manner as though they had
not been split into tines of the proper size required
taking care not to heat them so as to weld the other
tines are then drawn at right angles to the proper
size the middle tines are then opened to the
width required by a wedge or punch made for
the purpose the side tines are then brought
back to their place the whole shaped and come
for the use designed and then tempered like oth-
er steel forks and are handled for ^{the} use required

The principle of the improvement being to draw
the middle tines together by the same amount.

very difficult if not impossible in any other way and in this way four lines are made with nearly as much facility as three. These forks are found very useful for manure forks and may be used in the garden or for hay and many other purposes.

The mode and Manner of operation may be seen & understood by the Models or Specimens of the work deposited in the Patent Office of the United States

Dated at New Haven this 29th of May 1823
